(57) **CLAIM**

The ornamental design for a nail clipper, as shown and described.

DESCRIPTION

FIG. 1 is a perspective view of a nail clipper, showing our new design;

FIG. 2 is a perspective view of the nail clipper shown in an alternate configuration with one end open;

FIG. 3 is a perspective view of the nail clipper shown in an alternate configuration with another end open;

FIG. 4 is a perspective view of the nail clipper shown in an alternate configuration with both ends open;

FIG. 5 is another perspective view of the nail clipper;

FIG. 6 is a front view thereof;

FIG. 7 is a rear view thereof;

FIG. 8 is an enlarged left side view of the nail clipper;

FIG. 9 is an enlarged right side view of the nail clipper;

FIG. 10 is a top plan view thereof; and,

FIG. 11 is a bottom plan view thereof.

The broken lines shown in the drawings depict portions of the nail clipper that form no part of the claimed design.

1 Claim, 11 Drawing Sheets
